UNITED STATES PATENT OFFICE.

LUTHER PATTERSON, OF HARRIS COUNTY, TEXAS, ASSIGNOR TO HOWARD E. SMITH,
OF HARRIS COUNTY, TEXAS.

ROTARY.

Application filed May 16, 1924. Serial No. 713,826.

This invention relates to new and useful improvements in a rotary.

One object of the invention is to provide a rotary of the character described equipped 5 with an improved type of jaws for engaging with the upper joint or grief stem of the drill pipe for rotating said pipe in drilling.

Another object of the invention is to provide, in a rotary, pipe engaging jaws which 10 may be readily released from the grief stem when it is desired to break up the drill pipe or add additional joints thereto.

With the above and other objects in view, this invention has particular relation to certain 15 novel features of construction, operation and arrangement of parts, an example of which is given in this specification and illustrated in the accompanying drawings, wherein:

20 Figure 1 is a plan view.

Figure 2 is a cross sectional view taken on the line 2—2 of Figure 1; and,

Figure 3 is a cross sectional view taken on the line 3—3 of Figure 1.

25 Referring now more particularly to the drawings, wherein like numerals of reference designate similar parts in each of the figures, the numeral 1 designates the rotary bed plate, and the numeral 2 designates the rotary table which is mounted to rotate thereon. This table rides on the antifriction 30 rollers 3, which run in the race ways 4 and 5, in said bed plate and the underside of the table respectively. The under side of said 35 table has the marginal bevel gear teeth 6 which mesh with the driving pinion 7, fixed on the drive shaft 8.

The rotary table has the depending sleeve 9, therethrough which fits through the opening 10 in the bed plate and is provided to receive the drill pipe which is driven by said table.

40 On opposite sides of the table opening there are the cleats 11, 11, which are bolted to the table, and whose facing sides have the grooves 12, 12. There are the plate like jaws 13, 13, whose ends dovetail into said grooves and the adjacent edges of these jaws have the registering notches 14, 14, forming a

square opening to receive the grief stem. 50 These jaws are held in engagement with the stem by means of the space blocks 15, 15, which are fitted between the respective jaws and the opposing posts 16, 16, carried by the table. These blocks are of a size to hold the 55 jaws closely together in drilling, but smaller blocks may be used to space the jaws apart to permit the collars of the drill pipe to pass through in making up or breaking up said pipe, as illustrated in Figure 1. 60

The outer edges of these space blocks have the arcuate notches 17, 17, to receive said posts and to hold the blocks in proper position while drilling and they have the handles 18, 18, by means of which they may be 65 easily handled.

When it is desired to release the grief stem to pull the drill pipe, or to make up or break up the same, the space blocks may be removed and the jaws easily moved apart to 70 permit the handling of the drill pipe.

What I claim is:—

1. A rotary drilling machine including a rotary table having a central opening to receive a pipe, a track on said table, plate like 75 jaws movable toward and from each other along said track and whose facing edges are provided with aligned notches arranged to form a pipe receiving opening, posts on the table and space blocks fitted between the respective posts and the corresponding jaws. 80

2. A rotary drilling machine including a rotary table having a central opening to receive pipe, cleats on the table on opposite side of said opening and whose facing sides 85 are provided with grooves, plate like jaws whose ends fit into said grooves, the adjacent edges of said jaws having registering notches which form a polygonal opening, abutments carried by the table, one on each 90 side of said pair of jaws and spacer plates adapted to be fitted between the respective jaws and the corresponding abutment, the outer edges of said plates having notches to receive the corresponding abutments. 95

In testimony whereof I have signed my name to this specification.

LUTHER PATTERSON.
